(57) **CLAIM**

I claim the ornamental design for a surgical forceps, as substantially shown and described.

DESCRIPTION

FIG. 1 is a perspective view of a surgical forceps showing my new design;

FIG. 2 is a top view of a surgical forceps;

FIG. 3 is a top view of a tip portion of a surgical forceps;

FIG. 4 is a bottom view of a surgical forceps;

FIG. 5 is a bottom view of a tip portion of a surgical forceps;

FIG. 6 is a side view of a surgical forceps;

FIG. 7 is side view of a tip portion of a surgical forceps;

FIG. 8 is a front view of a surgical forceps, shown at an enlarged scale; and,

FIG. 9 is a back view of a surgical forceps, shown at an enlarged scale.
